UNITED STATES PATENT OFFICE.

JOSEPH DASCHBACH, OF PITTSBURG, PENNSYLVANIA.

DEVICE FOR HOLDING ROUNDS FOR ROLLING-MILLS.

SPECIFICATION forming part of Letters Patent No. 662,917, dated December 4, 1900.

Application filed December 23, 1899. Serial No. 741,428. (No model.)

To all whom it may concern:

Be it known that I, JOSEPH DASCHBACH, a resident of Pittsburgh, in the county of Allegheny and State of Pennsylvania, have invented a new and useful Improvement in Devices for Holding Rounds for Rolling-Mills; and I do hereby declare the following to be a full, clear, and exact description thereof.

My invention relates to mechanism for rolling cylindrical metal bars, generally known in the art as "rounds;" and it has for one of its objects to provide means for supporting the free ends of the rounds as they pass between the rolls.

15 A further object of my invention is to provide a supporting means for the free ends of the rounds which may be used in connection with a feeding-table in such manner as to prevent accidental engagement of the holding-tongs with any part of the table during the rolling operation.

It has been the usual practice in rolling heavy cylindrical metal bars, known as "rounds," to support them by means of chains and hooks depending from an overhead structure and to hold and guide the rounds by means of hand-manipulated tongs, so as to prevent any turning or twisting of the rounds on their axes during the rolling operation.

25 With such an arrangement the employment of a feeding-table was impracticable, and, furthermore, the weight of the bars operated upon and the care necessary to insure a proper guiding of the bars necessitated the employment of large numbers of skilled workmen.

In a former application filed by me April 4, 1899, Serial No. 711,641, I have set forth a self-operated means for holding, supporting, and guiding the bars during their passage through the rolls, a portion of which means I propose to employ in the apparatus constituting the subject-matter of this application. I have found, however, that it may be desirable under some circumstances to employ 45 a less-expensive mechanism than that set forth in my said prior application and one which involves the use of hand-operated tongs for holding the bars against twisting or turning. I have therefore devised the mechanism shown in the accompanying drawings, in which—

Figure 1 is a plan view of the entire mech-

anism. Fig. 2 is a view, partly in side elevation and partly in longitudinal section, of the mechanism shown in Fig. 1. Fig. 3 is 55 a detail view of portions of a set of rolls and three bars passing between the same. Fig. 4 is a transverse section on line IV IV, Fig. 1. Fig. 5 is a plan view of one portion of the mechanism shown in Figs. 1, 2, and 4, and 60 Fig. 6 is a longitudinal section on line VI VI of Fig. 5.

The details of construction as shown in the drawings will now be described, 1 being a pair of rolls having a plurality of passes of different size and adapted for rolling bars of rectangular or other non-circular form in cross-section into cylindrical bars or rounds. The rolls 1 are mounted in suitable frames 2, provided with adjusting means 3 for the bearings 65 of the rolls and with front guides 4 and rear guides 5, as is usual in this class of apparatus.

In front of the rolls 1 is mounted a feeding-table 6, provided with a series of rollers 7 and of sufficient length to receive any length of 70 bar that it may be desired to pass through any of the passes of the rolls 1. Hydraulic cylinders 8 or other suitable means are provided for raising and lowering the feeding-table, and the supporting frames or standards 9 are 75 mounted upon transversely-arranged guide-ways 10, so that the feeding-table may be moved laterally to accommodate it to different passes in the rolls. A similar table 11, provided with rollers 12, is mounted at the rear 80 side of the rolls 1 to receive the bars and raise them in order that they may be returned to the front of the rolls for further rolling. Suitable hydraulic cylinders and pistons 13 are 85 employed for raising and lowering the table 11. 90

In order to support the rear ends of the bars during the rolling operation, I provide two pairs of guide-rods 14, one at each side of the table 6 and supported in the standards 9, and above these standards and guide-rods 95 I mount a carriage or buggy 15, the body of which has a downwardly-projecting inclined forward end 16 and a substantially vertical rear end 17, which projects upwardly a sufficient distance from the bottom of the body to 100 act as a stop for the end of a bar or round 18 when brought into position on such body. The sides of the buggy are also provided with wings 19, which project outward over the

guide-rods in order to serve as guards to prevent the tongs 20 (indicated by broken lines) from coming into engagement with any of the stationary parts of the apparatus during 5 the movement of the buggy. The means for supporting the body of the buggy on the rods 14 comprise a pair of bars 21, suitably fastened to the bottom of the body and bent substantially at right angles to the main portion 10 at the sides of the body and having their ends bent parallel to the body portion, these latter portions being formed as axles 22 for grooved wheels 23, which are located between the guide-rods 14 and are fastened on the 15 axles by any suitable means.

In the operation of the mechanism the bar to be rolled is first placed in position upon the feeding-table with its rear end resting upon the buggy. It is then grasped by one 20 or more pairs of tongs 20 at or near the rear end, the tongs being manipulated by workmen employed for this purpose. After the bar has been carried through one pass of the rolls it is raised by means of the rear table 25 and its hydraulic mechanism and returned to the front table, which is raised to receive it. It is then given a quarter-turn in order to remove the longitudinal side fins that have been produced between the edges of the rolls, as 30 indicated in Fig. 3, and its outer end is placed upon the buggy. The bar is then carried through another pass in the rolls, after which it is returned to the front table and given a quarter-turn and either carried through the 35 same pass in the rolls or a smaller one, according to the size of the round desired, and this process is repeated until a perfectly cylindrical bar without fins is obtained.

I desire it to be understood that the details of construction and the mechanism may be 40 varied from what is shown, if desired, without departing from the spirit and scope of my invention. For example, my present improvement is adapted for use in connection with either two-high or three-high reversing 45 mills or with mills that are otherwise different in construction from that shown and described.

What I claim as my invention, and desire to secure by Letters Patent, is—

1. In mechanism for rolling cylindrical metal bars, the combination with suitable rolls and a feed-table, of guide rods or bars, supports therefor, and a buggy mounted on the guide-rods having side wings projecting 55 over the guide-rods and their supports.

2. In mechanism for rolling cylindrical metal bars, the combination with suitable rolls and a feed-table, of guide rods or bars, supports therefor, and a buggy mounted on 60 the guide-rods having an upwardly-projecting rear plate and wings projecting laterally over the guide-rods and their supports.

3. In mechanism for rolling cylindrical metal bars, the combination with suitable 65 rolls and a feeding-table, of guide-rods and a buggy mounted thereon having a body provided with laterally-projecting side wings, a downwardly-inclined front end and an upwardly-projecting rear end.

In testimony whereof I, the said JOSEPH DASCHBACH, have hereunto set my hand.

JOSEPH DASCHBACH.
